UNITED STATES PATENT OFFICE

151,314

DESIGN FOR AN ANGLE SOCKET

Charles J. Adams, Park Ridge, and Harold Z.
Benton, Woodstock, Ill.

Application November 12, 1946, Serial No. 134,720

Term of patent 14 years

(Cl. D26—1)

To all whom it may concern:

Be it known that we, Charles J. Adams, a citizen of the United States, residing at Park Ridge, Illinois, and Harold Z. Benton, a citizen of the United States, residing at Woodstock, Illinois, have invented a new, original, and ornamental Design for an Angle Socket, of which the following is a specification, reference being had to the accompanying drawing, forming part thereof.

Figure 1 is a perspective view of an angle socket, showing our new design;

Figure 2 is a side elevational view;

Figure 3 is an end elevational view; and

Figure 4 is a plan view.

We claim:

The ornamental design for an angle socket, as shown.

CHARLES J. ADAMS.
HAROLD Z. BENTON.
